UNITED STATES PATENT OFFICE.

HENRY W. RICHARDSON, OF WINCHESTER, MASSACHUSETTS, ASSIGNOR TO AUSTIN-WALKER COMPANY, OF BOSTON, MASSACHUSETTS, A CORPORATION OF MASSACHUSETTS.

HOSE-SUPPORTER.

No. 909,824.

Specification of Letters Patent.

Patented Jan. 12, 1909.

Application filed April 9, 1908. Serial No. 426,000.

To all whom it may concern:

Be it known that I, HENRY W. RICHARDSON, of Winchester, in the county of Middlesex and State of Massachusetts, have invented a new and Improved Hose-Supporter; and I hereby declare that the following is a full, clear, and exact description of the same, reference being had to the accompanying drawings, forming part of this specification.

This invention has reference to improvements in devices designed to be supported by or attached to articles of clothing and adapted to be engaged with and sustain hose.

The object of the invention is to improve the construction of slidably mounted hose supporters.

The invention consists in the peculiar features of construction and combination of parts which will hereinafter be more fully described and pointed out in the claims.

Figure 1, represents the improved hose supporter in use. Fig. 2 represents a front elevation of the improved hose supporter on an enlarged scale to more clearly show its construction.

In carrying this invention into practice the supporter is furnished with the cross member 5 of webbing of any desired length which is preferably adapted to be sewn to the lower edge of the corset. To the member 5 are secured the wire loops 6-6 by means of the bands 7-7 or in any other suitable and well known manner. Slidably engaged in said loops 6-6 and in the loops 8-8 of the web members 9-9 having hose engaging clasps or clamps 10-10 is the web member 11 having, when in the position shown, the vertical reaches 12-12 and the cross reaches 13 and 14 of which the reach 13 extends from the upper portion of one of the reaches 12 forward through one of the loops 6 and then diagonally downward to, and forwardly through one of the loops 8, thence upwardly to form the other of the vertical reaches 12, and forward through the other of said loops 6 and finally diagonally downward to the point at which it is engaged with the buckle 15 of the other end of said member 11 which end extends diagonally upward from the other of said loops 8.

Reference to the drawing will indicate that the member 11 is so slidably mounted in said loops 6-6 and 8-8 that it readily accommodates itself, to any irregular strain exerted on the member 9-9 by sliding through the guide loops 6-6 and 8-8 and that strain exerted on either of said members 9-9 will effect the drawing downward of the corresponding reach 12 and the diagonal reach 13 or 14 extending therefrom and the equivalent drawing upward of the other of said reaches, so that at all times the support is balanced and is yieldable to any strain. By the adjustment of the end of the reach 14 passing through the buckle 15 all of said reaches are correspondingly and simultaneously adjusted as to length.

Having thus described my invention, I claim as new and desire to secure by Letters Patent—

1. A hose supporter comprising a cross band, loops mounted thereon, independent hose engaging members having loops, and a single flexible member threaded through all of said loops and crossed diagonally.

2. A hose supporter comprising a pair of members each having a hose engaging device and a guide loop, a cross band having a pair of such guide loops, and a single flexible member slidably mounted in all of said loops and having vertical reaches and diagonal reaches, one end of said member having a buckle adapted to adjustably engage the other end thereof, for the purpose described.

3. A hose supporter comprising a cross band having guide loops thereon, a pair of hose engaging members having guide loops and a single flexible member slidably mounted in all of said loops and having vertical reaches and diagonal reaches of which one of the diagonal reaches is formed by the end portions of said flexible member extending forward through a pair of said guide loops, and a means for adjustably securing said ends together whereby the adjusting means is located on the front reach of said member, as described.

HENRY W. RICHARDSON.
